CEMENTING TOOL

Slayden R. Robinson, Whittier, and William J. Travers, Jr., Bakersfield, Calif., assignors to Halliburton Oil Well Cementing Company, a corporation of Delaware

Application February 17, 1940, Serial No. 319,546

12 Claims. (Cl. 166—1)

This invention relates generally to oil well tools and particularly to such tools as are used for carrying out cementing operations in oil wells.

In oil well drilling and production practice, it is necessary to perform cementing operations at various points in the well above the bottom of the well. These cementing operations usually entail the forcing of cement through holes in the casing, such holes being either originally provided in the casing as in the case of combination production strings of casing, or subsequently provided after the casing is in the well by any of the well known casing perforating methods. Such cementing operations require considerable time and equipment and with the apparatus now commonly in use necessarily result in leaving apparatus and cement in the well forming objectionable obstructions which must be drilled out. When it is desired to perform several cementing operations in the same well at various depths in the well, it is necessary for the ordinary apparatus to be run in and out of the well making several round trips in order to accomplish the multiple cementing operations. The cost of drilling the well and placing it on a production basis can be greatly reduced if these attendant disadvantages of ordinary cementing methods can be eliminated.

Generally it is an object of this invention to provide a new and improved tool for use in performing cementing operations in a well so that such operations may be carried out without the above mentioned and other disadvantages of the ordinary present day apparatus for performing cementing operations. It is also an object of this invention to provide a cementing tool which may be used for performing multiple cementing operations in a well at different depths without removing the tool from the well until all of the cementing operations have been completed, thereby eliminating the necessity of several round trips of the cementing apparatus into and out of the well as is necessary with ordinary equipment.

It is a further object of this invention to provide a cementing tool which may be operated in the well without leaving any apparatus in the well and without leaving any objectionable bridges or obstructions of any kind in the well. In this connection it is an object to provide a tool which is entirely removable from the well and further to provide a tool which may be flushed clean of excess cement and which is so designed that excess cement may be circulated

from and flushed out of the interior of the casing.

It is a further particular object of this invention to provide a tool of the type indicated which has a means for bypassing liquid to opposite sides of the casing engaging packers mounted on the tool during raising and lowering of the tool in the well, the means being controllable to close the by-pass means during the operation of cementing and for the performance of other operations. It is also an object to provide a tool of the type indicated having means for closing only a part of the by-pass means referred to immediately above.

15 It is a further object to provide a tool which may be used for flushing excess cement from the well and from the tool itself without increasing the pressure of the liquid in the well located below the lowermost packing element on the tool.

20 It is also an object to provide a tool which can be operated to determine whether the tool itself is located in a region of perforated or non-perforated pipe so that the tool can be used for accurately locating the so-called combination point cementing holes of combination casing.

25 It is a still further object to provide a tool which is capable of adjustment to permit of circulation of fluid through the tool and the well casing in several different ways.

30 These and other objects will be apparent from the drawings and the following description thereof. Referring to the drawings which are for illustrative purposes only:

35 Fig. 1 is an elevation partly in section of the upper portion of the tool, Fig. 1a is a sectional elevation of the intermediate portion of the tool, and Fig. 1b is a sectional elevation of the lower portion of the tool, each successive figure of the drawings being views of the successive portions of the tool;

40 Fig. 2 is a schematic sectional illustration of the tool shown in contracted position;

45 Fig. 3 is a schematic sectional elevation of the tool in the extended position shown opposite the combination point holes of a combination casing; and

50 Fig. 4 is a schematic sectional elevation of the tool in the intermediate position shown above the combination point holes.

More particularly describing the invention, the cementing tool embodies an inner tubular member 11 and an outer tubular assembly generally indicated by reference numeral 12. The outer assembly includes a slip mechanism 14, an up-

per by-pass section 15, a cementing section 16, a lower by-pass section 17 and a barrel 18. These sections making up the outer assembly of the tool are separated by stuffing boxes in which the inner tubular member is slidably received. Thus, the stuffing box 19 is provided between the upper by-pass section 15 and the cement section 16. Stuffing boxes 20 and 21 are provided at opposite ends of the lower by-pass section 17 and a stuffing box 22 is provided at the lower end of the barrel 18.

Each of the stuffing boxes (see stuffing box 19 of Fig. 1a) comprises a fitting 24 having an internal flange 25, suitable packing 26, and a packing gland 27 for holding the packing compressed 15 against the inner tubular member 11.

Referring to the details in construction of the tool, the upper end of the inner tubular member 11 is connected to a reducing coupling 30 which is connected to the lower end of an oil well 20 tubing or drill pipe 31 which may be considered as extending to the surface of the ground for raising and lowering the tool in the well. When the tool is first lowered in the well, the inner tubular member 11 is attached to the lower 25 stuffing box 22 to prevent movement of the inner tubular member relative to the outer assembly. To accomplish this attachment a shoe 32 is provided at the lower end of the inner tubular member. Links 33 and shear pins 34 detachably connect the shoe to the lower stuffing box 22. The shoe and stuffing box are provided with 30 interengaging clutch faces 35 and 36 so that the inner tubular member and outer assembly may be rotated as a unit. As will subsequently be 35 described, the tool is lowered in the hole with the parts attached as shown in Figs. 1, 1a and 1b and also Fig. 2 and subsequently the pins are sheared so that the inner tubular member may be moved relatively to the outer assembly.

The slip mechanism 14 provided at the upper end of the outer assembly is for the purpose of anchoring the outer assembly in the oil well casing at any desired point and this mechanism is of the ordinary construction employing the common pin and slot means for locking the slips in the unengaged position.

Below the slip mechanism there is provided a coupling 37 in which is mounted the upper by-pass section 15 which comprises a tubular member 38 provided with suitable openings or ports 39, 39' in its walls. The lower end of this tube 38 is mounted within the stuffing box 19. This construction forms what will be termed an upper chamber 40.

At the lower end of the stuffing box 19 there is provided a reducing coupling 42 into which is threaded a tubular member 43 which has mounted thereon the oppositely disposed packing members 44 and 45. These packing members are mounted facing each other so that they will cooperate with the well casing to form a packed off area which is substantially liquid tight against escape of pressure liquid upwardly or downwardly past the packers. The tube 43 is provided with suitable cement outlet openings 46 between the packing members. The tubular section 43 and the stuffing boxes 19 and 20 form what will be termed an intermediate chamber 47.

An inverted reducing coupling, indicated by reference numeral 48 is provided at the lower end of member 43 for attaching the stuffing box 20 thereto. Between stuffing boxes 20 and 21, 75 is the lower by-pass section 17 which comprises

the tubular member 49 which is provided with openings 50. The tubular member 49 and the stuffing boxes 20 and 21 cooperate to form a lower chamber 51.

A barrel 52 is provided between stuffing boxes 21 and 22 and this cooperates with said stuffing boxes to form a packed-off chamber 53.

The inner tubular member 11 is provided with three ports, the uppermost of these ports, assuming the tool to be in the contracted position in which it is shown in Figs. 1, 1a, and 1b, and Fig. 2 is within the chamber 40 of section 15 and is indicated by reference numeral 54. The intermediate port is positioned within the chamber 47 of cementing section 16 and is indicated by reference numeral 55, while the lower port is within the chamber 51 of lower by-pass section 17 and is indicated by reference numeral 56.

When the tool is first lowered in the well, the inner and outer assemblies are relatively immovable by reason of being temporarily connected through the medium of the links 33 and shear pins 34. As the tool is lowered in the hole, the ports 54 and 56 act as a by-pass means for bypassing liquid in the well past the packers 44 and 45 through the inner tubular member. In this connection, it is apparent that well liquid may enter the port 56 through the holes 50 in the tubular member 49 and may leave port 54 and pass out of openings 39-39' in the member 38 above the packers. When the tool is raised the flow of liquid is in the opposite direction.

To clearly illustrate and describe the operation of the tool, reference is made to Figs. 2, 3 and 4 where the tool has been schematically shown to facilitate illustration. In the operation of the cementing tool the tool is lowered into the well inside of the well casing 60 on the end of a string 40 of pipe 31 with the tool in the position in which it is shown in Fig. 2, that is in contracted position. The parts are held in this position by links 33 and shear pins 34. The tool may be readily lowered in the well by reason of the fact that in this position the liquid may bypass through the tool to opposite sides of the packers as heretofore described. When the tool has been lowered to the desired point the slips are set by slightly rotating the tubing 31 to cause the pin 50 of the slip assembly to become aligned with the elongated or major portion of the slot in the slip assembly and thereby release the slips for engagement with the well casing. After the slips have been set the inner tubular member may be freed from the outer assembly of the tool by a jarring action which will serve to break the shear pins.

In order to locate the tool at the proper point in the casing so that the packers are on opposite sides of, for example, the combination point cementing holes indicated by reference numeral 61 in Figs. 2, 3 and 4, such holes having been shown as having outwardly opening flap valves thereon, circulation of liquid is established downwardly 65 through the string 31 and the tool with the tool in its extended position or lowest position shown in Fig. 3. If circulation is impeded it is then obvious that the packers are in a region of non-perforated pipe since the only outlet for the downward circulating fluid from the inner tubular member is through ports 54, 55 and openings 48. The tool may then be raised until the combination point holes are located with the tool in the position shown in Fig. 3.

After the perforated region of the casing has

been found and the tool located with the packers on opposite sides of the perforations, as shown in Fig. 3, cement slurry or the like may be introduced at the upper end of the string of pipe 31 and pumped down through the string. It is preferable at first to have the tool in the contracted position of Fig. 2 or in the intermediate position of Fig. 4 so that the liquid in the pipe 31 below the introduced cement may be flushed out above and below the packers as would be the case with the tool in the position of Fig. 2, or may be flushed out merely above the packers as with the tool in the position of Fig. 4, until the cement reaches the tool. This operation prevents the objectionable displacement of such liquid out through the perforated casing between the packers where it is desired to perform the cementing operation. After the known quantity of liquid in the string of pipe 31 below the introduced cement has been circulated out and the cement has been pumped down to the tool, the tool is then extended to the position of Fig. 3 so that with continued pumping the cement will be forced down through the inner tubular member and out through the openings 54 and 55 of the inner tubular member and the openings 46 of the outer tubing to the region between the packers and then outwardly through the perforations in the casing to the desired region behind the casing. It should be noted in this connection that there is ample space between the inner tubular member and the outer tubing between the stuffing boxes 19 and 20 to permit the flow of cement or liquid from the inner tubular member through ports 54 and 55 to the cement holes 46 of the outer tubing. With the tool in extended position the lower port is blocked off within chamber 53.

After sufficient cement has been placed behind the casing the tool may be raised to a point above the perforated region as shown in Fig. 4, the slips set and reverse circulation of liquid established with the cementing tool still in the extended position of Fig. 3, the circulation of liquid being down between the casing and tubing 31 and the tool, the liquid flowing past the uppermost packer and in through openings 46 and into the inner tubular member until excess cement which may have found its way into the casing and which may remain in the region between the packers or in the tool is flushed out.

After this operation, or if preferred before this operation, the tool may be positioned with the inner tubular member in the intermediate position of Fig. 4 establishing communication between upper port 54 and openings 38 above the packers and circulation may be established the regular way down through tubing 31 and the inner tubular member and out through port 54 and opening 38 above the uppermost packer 44. It is to be pointed out that during this operation the lower by-pass port 56 is still within the packed off chamber 53 and therefore no pressure is placed upon the combination point holes or any portion of the casing below the packer 45. It is also possible to reverse the circulation with the tool in the intermediate position of Fig. 4, that is circulate liquid down the casing and into the tool through the upper by-pass ports 38-54 and to some extent past the packer 44 and into the tool through the openings 46-55.

If desired, circulation may also be established either in the regular way down through the tubing 31 or in the reverse direction down through the casing 60 and into the tool and up the inner tubular member with the tool in the contracted

position of Fig. 2. Establishment of circulation with the tool in this position may be desirable for performing certain operations in the well.

The tool may then be raised to some other point in the well where it is desired to perform a cementing operation merely by raising the string of pipe 31 thereby raising the inner tubular member 11 to its uppermost position in the outer tubular assembly, permitting by-pass of liquid to opposite sides of the packers.

While we have described a particular embodiment of our invention, it is to be understood that it is not intended to limit the invention to the exact construction shown, but it is intended to cover such changes as come within the scope of the claims.

We claim as our invention:

1. In a tool of the type described, the combination of: a tubular outer assembly; a pair of spaced packing members carried by said outer assembly adapted to engage a well casing; said outer assembly being provided with an upper, an intermediate and a lower opening in its walls, said openings being respectively positioned above, intermediate, and below said packers; means adapted for engagement with the well casing for releasably suspending said outer assembly; and an inner tubular member slidably receivable in said outer assembly, said tubular member being provided with three ports adapted to respectively communicate with the openings in said outer assembly when said inner tubular member is in one position, to communicate with only said upper and intermediate openings when said tubular member is in a second position, and to communicate with only said intermediate opening when said tubular member is in a third position.

2. In a tool of the type described, the combination of: a tubular outer assembly having an upper, a lower, and an intermediate chamber, said chambers each being provided with openings to the exterior of said assembly; a pair of packing members adapted to engage a well casing carried by said outer assembly one on each side of the opening in said intermediate chamber; means adapted for engagement with the well casing for releasably suspending said assembly; and an inner tubular member slidably receivable in said outer assembly, said tubular member having ports therein positioned to selectively register with certain of said chambers dependent upon the longitudinal position of said tubular member with relation to said outer assembly.

3. In a tool of the type described, the combination of: a tubular outer assembly having an upper, an intermediate and a lower chamber, said chambers each being provided with openings to the exterior of said assembly, said assembly having a packed-off region below said lower chamber; a pair of spaced packing members carried by said outer assembly adapted to engage a well casing, said packing members being disposed on opposite sides of the opening in said intermediate chamber; means adapted for engagement with the well casing for releasably suspending said outer assembly; and an inner tubular member slidably receivable in said outer assembly, said member being provided with an upper, an intermediate and a lower port positioned respectively in the upper, intermediate and lower chambers when said member is in one position, said inner tubular member being movable to bring said lower port into said packed-off region.

4. In a tool of the type described the combina-

tion as set forth in claim 3 in which the inner tubular member is further movable to bring said upper port into said intermediate chamber while maintaining said intermediate port in said intermediate chamber and maintaining said lower port in said packed-off region.

5. In a tool of the type described, the combination of suspension means for releasably engaging a casing wall; an outer tubular assembly associated with said suspension means and comprising an upper, an intermediate, and a lower perforate section and an imperforate section, said sections being separated by stuffing boxes thereby forming an upper, an intermediate, a lower and a closed chamber respectively; a pair of spaced packers mounted on said intermediate perforate section on opposite sides of the perforate region of said section; and an inner tubular member slidably receivable in said outer assembly and said suspension means, said inner tubular member being provided with an upper, an intermediate, and a lower port adapted to be positioned in said upper, said intermediate, and said lower chamber respectively when said inner tubular member is in one position, said inner tubular member being movable to bring said lower port into said closed chamber, and being further movable to bring said upper port into said intermediate chamber while maintaining said intermediate port in said intermediate chamber and said lower port in said closed chamber.

6. In a tool of the type described, a tubular outer assembly; four stuffing boxes in said assembly at spaced points; said assembly being provided with three perforate regions located respectively above the uppermost stuffing box, between the uppermost and second stuffing box, and between the second and third stuffing boxes; a pair of spaced packing members mounted on said outer assembly on opposite sides of the intermediate of said perforate regions; and an inner tubular member slidably receivable in said outer assembly and in said stuffing boxes, said member being provided with three spaced ports adapted to register with the respective perforate regions of said outer assembly when said inner tubular member is in the uppermost position relative to said outer assembly, said inner tubular member being movable to position the lowermost port between the third and fourth stuffing boxes while maintaining the other ports respectively in the region of the intermediate and uppermost perforate regions, and being further movable to cause the uppermost and intermediate ports to be positioned in the intermediate perforate region while maintaining the lowermost port between said third and fourth stuffing boxes.

7. In a tool of the type described, an outer tubing; a pair of spaced packers on said tubing adapted to engage a well casing; said outer tubing having an opening in its wall between said packers; an inner tubular member slidably mounted in said outer tubular member and being adapted to be attached at its upper end to a string of tubing for operating the tool in a well, said inner tubular member having a port communicating with said opening in said outer tubing; a shoe mounted on the lower end of said inner tubular member positioned below said outer tubing; clutch means formed on the lower end of said tubing and the upper end of said shoe adapted for engagement when said inner tubular member is in the uppermost position relative to said outer tubing whereby said outer tubing may be rotated by rotation of said inner

tubular member through the medium of said clutch means; and suspension means adapted for engagement with the well casing for releasably anchoring said outer tubing in a well casing, said means including inter-engaging means between said outer tubing and said suspension means for holding said suspension means inoperative, said interengaging means being releasable by rotation of said outer tubing.

8. In a tool of the type described, an outer tubing; a pair of spaced packers on said tubing adapted to engage a well casing; said outer tubing having an opening in its wall between said packers; an inner tubular member slidably mounted in said outer tubing and being adapted to be attached at its upper end to a string of tubing for operating the tool in a well, said inner tubular member having a port communicating with said opening in said outer tubing; a shoe mounted on the lower end of said inner tubular member positioned below said outer tubing; clutch means formed on the lower end of said tubing and the upper end of said shoe adapted for engagement when said inner tubular member is in the uppermost position relative to said outer tubing whereby said outer tubing may be rotated by rotation of said inner tubular member through the medium of said clutch means; means for releasably suspending said outer tubing from the well casing, said means including interengaging means between said outer tubing and said suspending means for holding said suspending means inoperative, said interengaging means being releasable by rotation of said outer tubing; means for securing said inner tubular member and said outer tubing together, said means being capable of being rendered inoperative by jarring said inner tubular member after said outer tubing is suspended from the well casing.

9. In a well cementing tool, a tubular assembly adapted to be suspended in a well on a string of pipe; a pair of spaced packers mounted on said tubular assembly; means establishing communication between the interior of said tubular assembly and the exterior thereof at a point between said packers; and means establishing communication between the interior of said tubular assembly and the exterior thereof at a point above said packers and at a point below said packers; said last mentioned means being controllable to close communication between the interior of said tubular assembly and the exterior thereof at a point below said packers while maintaining communication open between the interior of said tubular assembly and the exterior above said packers and intermediate said packers.

10. In a well cementing tool, an outer tubing; a pair of spaced packers mounted on said outer tubing; an inner tubular member slidably receivable in said outer tubing and adapted to be suspended on a string of pipe; means establishing communication between the interior of said inner tubular member and the exterior of said outer tubing in the region between said packers; means establishing communication between the interior of said inner tubular member and the exterior of said outer tubular assembly at a point above said packers and at a point below said packers, said inner tubular member being movable to control said last mentioned means and close communication between the interior of said inner tubular member and the exterior of said outer tubing below said packers while maintaining communication between the interior of said

inner tubular member and the exterior of said outer tubing above said packers and between said packers.

11. In a tool of the type described; the combination of: a tubular outer assembly; a pair of spaced packers on said outer assembly adapted to engage a well casing; said outer assembly being perforate in regions above, intermediate and below said packers; and an inner tubular member receivable and movable in said outer assembly and cooperating therewith to form isolated annular chambers in the outer assembly at each perforate region, said inner tubular member having ports therein positioned to selectively register with certain of said chambers dependent upon the position of said tubular member with relation to said outer assembly.

12. In a tool of the type described; the com-

bination of: a tubular outer assembly; a pair of spaced packers on said outer assembly adapted to engage a well casing; said outer assembly being perforate in regions above, intermediate and below said packers; and an inner tubular member receivable and movable in said outer assembly and cooperating therewith to form isolated annular chambers in the outer assembly at each perforate region, said inner tubular member having ports therein positioned to selectively register with certain of said chambers dependent upon the position of said tubular member with relation to said outer assembly; and means for releasably suspending said outer assembly from a well casing.

SLAYDEN R. ROBINSON.
WILLIAM J. TRAVERS, JR.
